UNITED STATES PATENT OFFICE

152,595

DESIGN FOR A SAFETY FISH GAFF

Harold Cederblad, San Francisco, Calif.

Application November 6, 1946, Serial No. 134,548

Term of patent 14 years

(Cl. D31—4)

To all whom it may concern:

Be it known that I, Harold Cederblad, a citizen of the United States, residing in the city of San Francisco, county of San Francisco, and State of California, have invented a new, original, and ornamental Design for Safety Fish Gaff, of which the following is a specification, reference being had to the accompanying drawing, forming part thereof, in which:

Figure 1 is a side elevation of a safety fish gaff, showing my new design, the hook being extended;

Figure 2 is a side elevation thereof as viewed from the opposite side of Figure 1, the hook being shown in retracted position;

Figure 3 is an end elevation as viewed from the line III—III of Figure 2; and

Figure 4 is a perspective view showing the hook retracted.

I claim:

The ornamental design for a safety fish gaff, substantially as shown.

HAROLD CEDERBLAD.
